Patented Mar. 27, 1917.

UNITED STATES PATENT OFFICE.

ALBERT E. AINSLIE, OF BRASHEAR, MISSOURI.

MEDICINE-CARD.

1,220,926.

Specification of Letters Patent.

Patented Mar. 27, 1917.

Application filed February 15, 1916. Serial No. 78,414.

To all whom it may concern:

Be it known that I, ALBERT E. AINSLIE, a citizen of the United States, and a resident of Brashear, in the county of Adair 5 and State of Missouri, have invented a new and useful Improvement in Medicine-Cards, of which the following is a specification.

My invention is an improvement in medicine cards, and the invention has for its 10 object to provide a card of the character specified, having means for permitting the same to be hung up on the wall of a sick room, wherein the card is provided with a scale representing the divisions of time, and 15 a series of marking means or indicators for coöperating with the scale to indicate certain predetermined hours or other divisions of time, the said indicators being distinguished from each other by difference in 20 color or the like to represent different medicines to be given, and wherein the card and the indicators have coöperating means for permitting the indicators to be supported at predetermined points of the scale.

25 In the drawings:—

Figure 1 is a perspective view of the card in use, and

Fig. 2 is a front view of the card.

The present embodiment of the invention 30 comprises a card which may be made of any suitable material, as for instance, paste board, paper, celluloid or sheet material of any character, the said card comprising a rectangular portion 1 having a substantially 35 triangular extension 2 at its top, the extension being integral with the body or rectangular portion 1, and having at its apex an opening 3 for engaging a nail 4, or the like, to support the card in a position where 40 it may be easily consulted.

The card is provided with a longitudinally 45 extending slot or passage 5, near the top of the rectangular portion 1 and parallel with the bottom edge of the said portion, and 50 a scale is arranged on the front face of the card just below this passage or slot. This scale 6 as shown, is formed by vertical lines spaced apart at equal distances from each other and of varying lengths to distinguish 55 different divisions of time.

In the present instance, the scale has twelve (12) primary sub-divisions representing the twelve hours of a half day, and each of these primary sub-divisions is di-

vided into two secondary sub-divisions representing the half hours, and the lines on the scales designating the half hours are about 55 half the length of the lines designating the hours.

Each of the secondary sub-divisions is 60 divided into two tertiary sub-divisions representing the quarter hours, and at each 65 of the lines designating the primary sub-divisions a numeral is arranged, the said numeral being interposed in the length of the line as shown. The lower side edge of 70 the passage or slot 5 is formed into teeth or is notched as indicated at 8, at each of the lines forming the scale and the indicators to be described are arranged to co-operate with the notches or teeth to indicate 75 the hours when medicine is to be administered.

The card 1—2 is provided near its lower 80 edge and at its center with an opening 9, and a series of cords 10—11 and 12 are connected with the opening, the end of each 85 cord being tied in the opening as shown. The cords are of different colors, the cord 10 in the present instance being green, the cord 11, blue and the cord 12, red, and each of the cords is provided at its free end with a weight 13 in the form of a ball or the like, for holding the cord taut.

The cords are of such length that any cord 85 will extend from the opening 9 to the opposite ends of the slot or passage 5, and will pass through the said slot or passage from rear to front and will depend below the lower edge of the card at the front. 90 Since each of the lines forming the scale has a notch or recess at its upper end it will be obvious that when the cords are engaged with the notches or recesses as indicated in Fig. 2, the cord in front of the card will 95 hang directly above the line at the notch or recess.

The cords extend from the opening 9 in rear of that portion of the card below the slot or passage 5 through the said slot or 100 passage and below the lower edge of the card. The cords may be engaged with any notch or recess merely by lifting up the cord and moving it to the proper notch. Each cord is designed to represent a particular 105 medicine to be given at predetermined intervals, and when the dose of medicine represented by any particular cord or indicator

has been given the cord will be moved to the notch representing the sub-divisions of time when the said medicine is to be again given.

In Fig. 1 three packages 14—15 and 16 of medicine are shown, and each is provided with a knot or bow 17 of ribbon or cord which is colored, the ribbons or bows on the several packages being differently colored and of the same color as the several indicators. For instance, the ribbon on the package 14 might be green, that of the package 15 blue and that of the package 16 red. If for instance the medicine in the package 14 is to be given every four hours, that in the package 15 every half hour and that in the package 16 every hour the cord or indicator 12 will be arranged on the hour mark.

If the nurse for instance should come on duty at one o'clock the indicator 12 would be placed after the one o'clock dose on the line designated by the numeral 2, and each time that the medicine is administered the indicator will be moved to the succeeding hour.

In the same manner the indicators 10 and 11 will be used, the indicator 10 being moved four primary sub-divisions at each administration of medicine represented by the indicator. The indicator 11 would be moved one secondary sub-division for each dose administered. While it is obvious that any

number of cords or indicators might be used in connection with the card, as a rule three will be sufficient.

The nurse or other person in charge can determine at a glance the time for administering medicine and also determine at a glance whether or not any particular medicine or any particular dose of medicine has been omitted.

I claim:—

A device of the character specified, comprising a card having means for permitting the same to be suspended and having a longitudinally extending slot or passage, said slot or passage being horizontal when the card is suspended and the card having a scale below the slot or passage and the lower wall of the said slot or passage being notched or recessed at each indication of the scale, said card having an opening at its center and near its lower edge and a series of cords of different colors tied at one end in the opening and provided at the other end with a weight and of a length to extend upwardly from the opening behind the card through the slot or passage and with the weight depending below the card at the front thereof.

ALBERT E. AINSLIE.
